CLAIM

The ornamental design for an air preheater, as shown and described.

DESCRIPTION

1. Air preheater
FIG. 1.1 : Front
FIG. 1.2 : Enlarged view of upper part of the front view
FIG. 1.3 : Enlarged view of lower part of the front view
FIG. 1.4 : Back
FIG. 1.5 : Enlarged view of upper part of the back view
FIG. 1.6 : Enlarged view of lower part of the back view
FIG. 1.7 : Left
FIG. 1.8 : Enlarged view of upper part of the left view
FIG. 1.9 : Enlarged view of lower part of the left view
FIG. 1.10 : Right
FIG. 1.11 : Enlarged view of upper part of the right view
FIG. 1.12 : Enlarged view of lower part of the right view
FIG. 1.13 : Top
FIG. 1.14 : Bottom
FIG. 1.15 : Perspective
FIG. 1.16 : Enlarged view of upper part of the perspective view
FIG. 1.17 : Enlarged view of lower part of the perspective view

The product of the design is an air preheater; the design is used for preheating air; the design point is the shape; and the representative view is the perspective view.

The broken lines in the figures depict portions of the air preheater which form no part of the claimed design.
